G. H. DICKSON

BAFFLE CONSTRUCTION

Original Filed Dec. 20, 1919

Patented Dec. 1, 1925.

1,563,969

UNITED STATES PATENT OFFICE.

GEORGE H. DICKSON, OF CHICAGO, ILLINOIS, ASSIGNEE TO THE BABCOCK & WILCOX COMPANY, OF BAYONNE, NEW JERSEY, A CORPORATION OF NEW JERSEY.

BAFFLE CONSTRUCTION.

Application filed December 20, 1919, Serial No. 846,415. Renewed October 26, 1925.

To all whom it may concern:

Be it known that I, George H. DICKSON, a citizen of the United States, residing at Chicago, in the county of Cook and State 5 of Illinois, have invented certain new and useful Improvements in Baffle Constructions, of which the following is a specification.

My invention is an improvement over the 10 construction of baffles disclosed in my application Serial No. 238,097, which was filed in the Patent Office on or about June 4, 1918, and is particularly applicable to the installation of baffles for steam boilers.

15 My invention will best be understood by reference to the accompanying drawings, in which Figure 1 is a sectional elevation across the water tubes of a steam boiler on line 1—1 of Fig. 3, and showing, in elevation, the first stage of building a baffle according to my invention and with some of the parts, such as the bridge wall of the boiler, omitted for clearness, one of the walls partially broken away and the flame-plate 20 back of the same, and also showing the spacing strips disposed in position between the boiler tubes; Fig. 2 is a view, similar to Fig. 1, illustrating the spacing strips partially withdrawn and the plastic material 25 poured into the space from which the strips have been withdrawn; Fig. 3 is a longitudinal section showing a bank of water tubes in elevation and a baffle, which has been constructed in accordance with my invention, arranged transversely of the tubes, and Fig. 4 is a cross section taken on the line 4—4 of Fig. 1 looking in the direction of the arrows and with the front wall partially broken away to disclose the hardened plastic material behind the same.

40 I have illustrated my invention in connection with the forming of a baffle for the tubes 10 of a water tube boiler, which baffle, in the form illustrated, comprises a double wall of tiling spaced apart, with the space therebetween filled with a suitable plastic, hardening material, such as a mixture of finely ground fire-brick, asbestos fibre, Portland cement and fire-clay, or with 45 any form of the so-called high temperature cements. The forming of a baffle of this character around a bank of tubes presents difficulties for the reason that the outer walls are made up of tiles fitted between the 50 tubes, the tiles being diamond-shaped in

form and recessed at the corners to fit around the tubes by which they are supported. It is difficult to build up a wall of tiles formed of such sections having a uniformly even face, and when built, the wall 55 is readily displaced. Any irregularities occurring in the wall, such as would be caused by imperfectly forming the wall or by the wall buckling during the pouring operation, would be imparted to the intervening wall 60 of poured plastic material and give it an irregular form. In accordance with my invention, the outer walls are spaced apart by strips while being built, and the strips 65 are gradually withdrawn as the plastic material is being poured between the walls, so that the outer walls are maintained in properly spaced relation.

70 In the embodiment of my invention here illustrated, I first build up two walls 11 and 12 of the usual tile blocks, spaced apart and fitted around and supported upon the boiler tubes, with spacing strips 13 disposed between the walls and extending diagonally 75 across the tubes. The baffle extends upwardly from the bridge-wall 14. In the form here shown, a flame-plate 15 is located against the refractory wall 12, the bottom 80 of the flame-plate being held in position by an angle-iron 16 which engages the top of the wall 14. The walls are surrounded on the sides and at the bottom by boards or other suitable members 17 and 18, respectively, which form, with the refractory walls 11 and 12, a form within which the 85 plastic material is to be poured or otherwise filled in. The spacing strips 13 may pass through diagonal slots 18^a formed in one of the boards or members 17—for example, the 90 board at the left—as shown in Fig. 2.

95 Now, in order to pour the baffle of plastic, hardening material into the form shown in Fig. 1, the spacing strips are partially withdrawn from one side and from the bottom, 100 as best shown in Fig. 2, to create a free flow area for the plastic material 20, into which the material is poured or otherwise filled in and which thus finds its way to the bottom of the mold, as shown in Fig. 2, the portions 105 of the strips remaining between the walls serving to maintain the walls in spaced relation. The spacing strips are then further withdrawn to increase the free flow area and the process continued until the space 110 between the walls is filled.

It will be understood that the process embodying my invention is usually carried out after the boiler tubes have been installed and before the boiler setting has been completed. When the poured material has hardened, the retaining boards 17 and 18 are removed, and the permanent wall 21, as shown in Fig. 4, may then be built around the tubes.

10. If the bridge wall 14 is used in connection with the baffle, it may be built either before or after the baffle is formed. If it is built before, the strip 18 will not be used, the plastic material being poured directly 15 against the top of the wall 14. If it is built after, then the strip 18 will be removed after the plastic material is poured and has hardened and its space preferably will be filled before the wall 14 is built.

20. While I have illustrated my invention in conjunction with a baffle having two walls of refractory material, it will be understood that it is equally applicable to a baffle that is formed by pouring or otherwise filling in 25 the plastic material between the iron flame-plates and a single line of tile, or it would be applicable to pouring the plastic material between removable forms placed at each side, which removable forms could be taken 30 away after the plastic material had set and hardened.

While I have herein shown and described one modification of my invention, I do not desire to be limited to the exact arrangement 35 shown and described, but seek to cover, in the appended claims, all those modifications which come within the true spirit and scope of my invention.

What I claim and desire to secure by 40 Letters Patent of the United States is:

1. The method of installing a baffle across tubes and between walls extending transversely of the tubes, which consists in spacing the walls apart by strips, filling in hardening plastic material within the space between the two walls, and withdrawing the strips as the filling in progresses.

2. The method of installing a baffle across tubes and between walls extending transversely of the tubes, which consists in spacing the walls apart by strips extending diagonally across the tubes, filling in hardening plastic material within the space be-

tween the two walls, and withdrawing the strips as the filling in progresses.

3. The method of installing a baffle across tubes and between walls extending transversely of the tubes, which consists in spacing the walls apart by strips extending diagonally across the tubes, filling in hardening plastic material within the space between the two walls, and gradually withdrawing the strips from one side and from the bottom as the filling in progresses.

4. The method of installing a baffle across tubes and between walls extending transversely of the tubes, which consists in spacing the walls apart by strips extending diagonally across the tubes, withdrawing the strips to form a free flow area from the top to the bottom of the enclosed space, filling in hardening plastic material into the free flow area, and further enlarging the flow area by gradually withdrawing the strips as the filling in proceeds.

5. The method of installing a baffle across tubes, which consists in forming a mold extending transversely of the tubes with spacing strips between the side walls of the mold, partially withdrawing the strips to create a free flow area from the top to the bottom of the mold, and filling in hardening plastic material into the free flow area.

6. The method of installing a baffle across tubes, which consists in forming a mold extending transversely of the tubes with spacing strips between the side walls of the mold and extending diagonally across the tubes, partially withdrawing the strips to create a free flow area from the top to the bottom of the mold, and filling in hardening plastic material into the free flow area.

7. The method of installing a baffle across tubes, which consists in forming a mold extending transversely of the tubes with spacing strips between the side walls of the mold and extending diagonally across the tubes, partially withdrawing the strips to create a free flow area from the top to the bottom of the mold, filling in hardening plastic material into the free flow area, and enlarging the free flow area by further withdrawing the strips as the pouring progresses.

GEORGE H. DICKSON.
